UNITED STATES PATENT OFFICE.

ABRAHAM SACKS, OF BROOKLYN, NEW YORK.

TASSEL.

Application filed June 23, 1926. Serial No. 118,124.

This invention relates to tassels.

An object of the invention is to provide an ornamental and attractive tassel in which the parts are securely held together on an 5 improved tassel head.

With these and other objects in view, the invention consists in certain novel features of construction and combinations and arrangements of parts, which will be more 10 fully hereinafter described and pointed out in the claim.

In the accompanying drawings—

Figure 1 is a view in longitudinal section, 15 illustrating my improved tassel;

Figure 2 is a view in elevation of the upper portion of the tassel, showing the same partly broken away;

Figure 3 is a view in transverse section on the line 3—3 of Figure 1.

Referring more particularly to the drawings, the tassel comprises a bunch 5, and 20 6 designates my improved mold. The mold 6 has its upper end rounded, as indicated by the reference numeral 7, the lower end 25 thereof being formed with a square or straight edge 8.

Adjacent the lower end of the mold 6 an annular groove 9 is provided, and said groove is adapted to receive cords or wires 30 10 for securing the bunch 5 to the mold 6.

The mold 6 is further provided with a longitudinal central passage 11, the purpose of which will hereinafter be more fully described.

After the bunch 5 has been tied into the mold 6 a fringe 12 for the mold is applied. 35 This fringe comprises a wire strand 13 covered with silk 14. This silk covered wire strand 13 is then wrapped in a coil of the desired shape or form to receive the mold 6 in such a manner as to have a snug fit thereon. This fringe 12 is adapted to be of sufficient length to cover the upper portion of the mold and extend approximately on a line 40 with the top edge of the annular groove 9.

After the fringe 12 has been applied to the mold, a suitable cord 15 is attached to

the tassel 9, said cord being passed through the longitudinal passage 11 in mold 6 and has its free ends knotted, as indicated by 50 the reference character 16. In order to prevent the cord 15 from passing entirely through the mold 6 and at the same time to provide for retaining the fringe 12 in position upon the mold, the cord 15 is knotted, 55 as indicated at 17, at the top of the mold.

From the foregoing it will be apparent that the present invention provides a tassel which may be readily assembled, and on 60 which the tassel at all times will remain in position upon the head or mold, and at the same time, in a tassel constructed in accordance with the present invention, the fringe 65 may be readily removed by a loosening of the knot 17.

To give an additional ornamental and attractive appearance I locate around the mold 6 between the end of the coiled wire 12 and the bunch 5 what is known in the art 70 as a wired frill 18.

Various slight changes and alterations might be made in the general form of the parts described without departing from my invention and hence I do not limit myself to the precise details set forth but consider myself at liberty to make such slight changes 75 and alterations as fairly fall within the spirit and scope of the appended claim.

I claim:

A tassel, comprising a mold having a longitudinal passage therethrough, and an annular groove adjacent its lower end, a bunch secured in said groove, a coiled silk covered wire constituting a resilient fringe located around the upper portion of the mold, a 80 wired frill interposed between the fringe and the upper edge of the bunch, a cord having its upper end projected through the longitudinal passage of the mold, and knots in said cord at both ends of the passage, one 85 of said knots serving to hold the fringe on the mold.

ABRAHAM SACKS.
